UNITED STATES PATENT OFFICE

FRANK H. NEFF, OF CLEVELAND, OHIO, ASSIGNOR TO THE ELECTRIC RAILWAY IMPROVEMENT COMPANY, OF CLEVELAND, OHIO, A CORPORATION OF OHIO

RAIL BOND AND METHOD OF MAKING SAME

Application filed September 19, 1919. Serial No. 324,905.

The present improvements relate to a rail bond of the type in which the body is made of copper or other metal having a relatively low fusing point, and the terminal or terminals then formed by attaching to the end or ends of such body portion a plate or jacket of metal, for example iron or steel, having a relatively high fusing point, approaching that of the rail to which the bond is to be attached. Bonds of this type are usually thus attached to the rail through the medium of fused metal derived from an arc pencil, in the fashion described for example in U. S. Patent No. 1,168,753 to Benjamin F. Silliman, dated January 18, 1916.

The object of the present invention is to provide a bond having a terminal of the sort described, that may be readily applied to the ends of the conductor body, the latter usually consisting of a stranded cable, as is well known. A further object is to provide a terminal that readily lends itself to the method of attaching, wherein an arc pencil is used, as just described. At the same time of course it is desirable to insure a thorough electrical connection between conductor and terminal, and between the latter and the rail.

To the accomplishment of the foregoing and related ends, the invention, then, consists of the means and steps hereinafter fully described and particularly pointed out in the claims, the annexed drawings and the following description setting forth in detail certain means embodying the invention, which, however, constitute but one of the several ways in which the principle of the invention may be used.

In said annexed drawings:—

Fig. 1 is a front elevation of a bond terminal embodying my present improvements; Fig. 2 is an end view of the same, and Fig. 3 a vertical section thereof, as applied to a rail; while Figs. 4 and 5 are rectangularly related sections showing the terminal in the course of its manufacture; and Figs. 6 and 7 are inside and outside views respectively of the terminal member, Fig. 8 a vertical section of the same, separate and apart from the conductor to which such member is applied in the completed article; and Figs. 9 and 10

are a front elevation and vertical section of a modified construction.

As previously indicated, the body 1 of the bond is of familiar type, consisting of a flexible stranded cable (or plural cables) of copper, aluminum or like metal of high electrical conductivity, the ends of which are designed to be connected across a joint in the rails. To each such end is attached a terminal member of the sort which constitutes the feature of present interest. This member 2 is shown in Figs. 6, 7 and 8 in the form it has previous to being applied to the ends of the conductor or bond body; in Figs. 4 and 5 in course of application to such ends; in Figs. 1 and 2 as thus applied; and in Fig. 3 as in course of attachment to the rail. Such terminal member is of ferrous metal, preferably a steel forging, having a solid head portion 3 and a flanged portion 4 integral therewith, such flanged portion in turn having lateral extensions 5 adapted to be folded over so as to surround the end of the conductor. Both head and flange, as forged up, are preferably formed with an oval depression 6 in which the end of the conductor, (or the ends if two or more cables compose such conductor), as in the specific construction illustrated), may be placed, and it will be noted that the head extends laterally approximately equal distances beyond such depression or recess 6 in opposite directions therefrom, also that the under sides of such laterally extending head-portions slant downwardly to the points where they merge with the flange portion. The walls of the depression in the latter are thereby reinforced to a degree, preventing their flattening out when the end of the conductor body is brazed or welded in such recess, which will be presently described. A strip of brass will be wrapped around the cable ends before they are inserted in the terminal member, or equivalent braze material is otherwise suitably introduced. Thereupon, by folding over the lateral extensions of the flange, such ends are clamped more or less firmly to the terminal. The preliminarily assembled terminal is then placed between electrodes 7 and 8 as shown in Figs. 4 and 5, which are included in a suitable electric cir-

cuit 9, so that heat will be generated sufficient to partially fuse or soften both the end of the conductor and the flange portion of the terminal surrounding the same, together with the interposed braze material. Through the exercise of a proper degree of pressure, when this stage is reached, such flange is consolidated with the stranded material of the bond, and the latter wholly fills the tubular portion of the terminal which the folded over flange in effect provides.

In order to attach the terminal to a rail, the latter is brought, preferably with the side on which the end of the conductor is exposed, i. e. the side corresponding with the open face of the terminal in its original form, disposed towards the rail face. The face of the terminal in question is preferably formed at an angle, as shown in Figs. 2 and 4, so that the upper face of the terminal inclines inwardly 20 the rail 10. A pocket is thus in effect provided to assist in retaining the fused metal 11 of the arc pencil 12, so that a body of metal from such pencil is built up on the ledge 25 which the upper face of the terminal presents. The finished terminal, after the bond is attached, will then present the appearance shown in cross-section in Fig. 3.

If desired, the lateral extensions 5 of the terminal may be omitted and the ends of the cables be left laterally exposed as shown in Figs. 9 and 10, after they have been welded or brazed as previously described in the recess 6 in such terminal, or, instead of bending these extensions inwardly before the step in question, the cable ends may be first welded or brazed and such extensions then folded over. In each of the several constructions described, the body of the terminal, it will be observed, affords a complete protection for the ends of the cables from the intense heat of the arc when the band is being attached to the rail.

It will be understood that the term welded as herein employed has reference to the more or less homogeneous mechanical juncture secured between the copper cables and the steel, or ferrous metal terminal, irrespective of whether braze be used or not in making such juncture.

Other forms may be employed embodying the features of my invention instead of the one here explained, change being made in the form or construction, provided the elements stated by any of the following claims or the equivalent of such stated elements be employed, whether produced by my preferred method or by others embodying steps equivalent to those stated in the following claims.

I therefore particularly point out and distinctly claim as my invention:—

1. As an article of manufacture, a rail-bond comprising a conductor body of a metal of relatively low fusing point, and a termi-

nal of a metal of relatively high fusing point, said terminal having a head formed with a depression in one face and having solid oppositely directed extensions on either side of such depression, and a flange depending from said head in line with such depression, the end of said conductor being received in such depression and said flange substantially surrounding such conductor end.

2. As an article of manufacture, a rail-bond comprising a conductor body of a metal of relatively low fusing point, and a terminal of a metal of relatively high fusing point, said terminal having a head formed with a depression in one face and having solid oppositely directed extensions on either side of such depression and a flange depending from said head in line with such depression, the end of said conductor being received in such depression and terminally abutting against said head and said flange having lateral extensions folded around such conductor-end.

3. A terminal for a rail bond conductor comprising a head formed with a depression in one face and having solid oppositely directed extensions on either side of such depression, and a flange depending from said head in line with such depression, said flange being formed with a lateral extension.

4. A terminal for a rail bond conductor comprising an elongated head formed with a depression in one face and having solid oppositely directed extensions on each side of such depression, and a flange depending from said head in line with such depression, said flange being formed with a lateral extension on each side.

Signed by me, this 16th day of September, 1919.

FRANK H. NEFF.
